ROSCOE ALLEN MERROW, OF FARMINGTON, MAINE.

CAR-COUPLING.

SPECIFICATION forming part of Letters Patent No. 320,152, dated June 16, 1885.

Application filed September 30, 1884. (No model.)

To all whom it may concern:

Be it known that I, ROSCOE ALLEN MERROW, of Farmington, in the county of Franklin and State of Maine, have invented a new 5 and Improved Car-Coupling, of which the following is a full, clear, and exact description.

The objects of my invention are to provide for coupling cars automatically as they come 10 together, and for uncoupling the cars from their tops or from the ground at either side without requiring the trainmen to go between the cars and expose themselves to injury, and also to promote durability of the cars and 15 couplings by relieving the shocks incident to coupling or uncoupling, or in traffic over the road.

The invention consists in particular constructions and combinations of parts of the 20 car-couplings, including an arrangement of the opposite draw-heads of the same car to slide endwise and against buffer-springs, and connected by a draw-bar, and an arrangement of buffer-springs behind the opposite heads of 25 the draw-bar, whereby the coupling-bar, draw-heads, and cars will be relieved of breaking shocks or strains in coupling or while on the road. The invention comprises also a contrivance of an uncoupling-frame and 30 levers to uncouple the cars from their top or from either side, all as hereinafter fully described and claimed.

Reference is to be had to the accompanying drawings, forming part of this specification, 35 in which similar letters of reference indicate corresponding parts in all the figures.

Figure 1 is a broken side elevation of parts of a box or freight car, showing the draw-heads or couplings at opposite ends of the car 40 and one of the couplings in longitudinal sectional elevation. Fig. 2 is an end view of the car and coupling with the coupling-bar in cross-section. Fig. 3 is a side elevation of the coupling-bar drawn to a larger scale; and 45 Fig. 4 is a vertical section on the line $x-x$, Fig. 1, with the parts in larger size.

My improved couplings may be applied to railway passenger-cars or to platform freight-cars, but I represent it in connection with an 50 ordinary box freight-car.

The draw-heads A of the couplings are supported so as to have a limited endwise move-

ment beneath the car-body B, by the strong strap-irons C, which are bolted at c to the car-body or frame, and behind each draw-head is 55 fixed to the car-body the timber or metal plate D, which may be the inner end of a case, A³, in which the draw-head A slides.

E is the draw bar or rod which passes through apertures d a in the plate D and the 60 end of the draw-head, respectively, and has a head, e, which loosely fits the rear chamber or recess, F, of the draw-head, between which head e and the end wall of the draw-head is placed on the draw-bar E the spring G, which 65 may be compressed by the coupling-bar H as it enters the chamber F in coupling the cars, as hereinafter more fully explained.

Behind the back end of the draw-head A and between it and the fixed plate D, is placed 70 on the draw-bar E the heavy spring I, which acts as a buffer to the back movement of the draw-head as the cars come together for coupling.

The draw-heads A A at the opposite ends 75 of the car are counterparts of each other, and have like arrangements of buffer-springs G I, as above described, and I extend the draw-bar, having a head, e, at each end, from one draw-head to the other.

The draw-bar E may, of course, be a continuous bar; but I prefer to make it in two parts or sections having right-and-left or reverse screw-threads e' on their inner or adjacent ends to enter the threaded nuts j j of a 85 turn-buckle, J, which construction allows the opposite heads e e of the draw-bar E to be forged or welded solidly to the bar, and also permits longitudinal or lengthwise adjustment of the draw-bar to secure its best action in both 90 draw-heads with relation to the opposite springs G and the coupling-bar H entering either of the draw-heads, and also allows the more easy connection of the draw-bar to the draw-heads and of the draw-heads to the car. 95

I make the draw-head A in two parts or sections, A' A², joined horizontally on the line a', and connected to each other by bolts a², or in any other approved way.

The sectional construction of the draw-head 100 makes it easier in casting it to form the rear chamber, F, the front bell-mouthed recess or cavity, K, and the stud or horn L, which stud projects upward from the floor of cham-

ber F, so as to be engaged by the shoulder *h* of the tapering head H' of the coupling-bar H, to effect the coupling of the cars.

A spring, M, fastened at *m* to the draw-head, 5 presses the coupling-bar H down to hold or lock its head H' behind the stud L, as shown in Fig. 1, and also serves to hold the projecting end of the coupling-bar up to enter the opposing draw-head. The free end of the 10 spring is turned up, so as not to catch on the head of the coupling-bar as it enters and leaves the draw-head.

The side walls of the recess K converge backward to the throat l above the stud L to 15 guide the head of the coupling-bar to and through said throat l should the entering coupling-bar stand at a greater or less angle up or down or to either side, thereby insuring the automatic coupling as they come together of cars whose draw-heads stand at different heights or out of line sidewise with each other, and as the head H' of the coupling-bar enters the chamber F it strikes the head e of the draw-bar E, which yields with 20 the spring G to cushion the blow and prevent bending or breaking of the coupling-bar.

For uncoupling the cars I provide a U-shaped frame, N, which is passed by its side arms, *n n*, up through the part A' of the draw-head and has a lower cross-bar, *n'*, which comes below the head H' of the coupling-bar H when the frame N hangs by its upper cross-piece, O, from the top of the draw-head. (See Fig. 4.) I prefer to hold the cross-piece O to the frame N by nuts *o*, screwed on the ends of the arms *n n* above the cross-piece, as shown.

To the cross-piece O (or frame N) is connected at *p* the rod or bar P, which is guided in staples or eyes Q fixed to the car-body and 40 extends to the top of the car, from which point the frame N may be lifted by drawing up the rod P to carry the coupling-bar head H' by the cross-bar *n'* above the stud or projection L and against the tension of the spring M to 45 allow the cars to be drawn apart.

To provide for uncoupling the cars by trainmen standing on the ground at either side of the car, I pivot on a pin, *r*, fixed to the rod P, the lever R, the opposite arms of which extend toward either side of the car and pass through long keepers or staples S S, outside of which the lever R carries the fixed handles T T, which project about at right angles from the lever, so as conveniently to be reached 50 from the side of the car, said handles T being entirely within the plane of the sides of the car, and so as to be guarded from injury by contact with any object when the car is moving on the road or by moving objects when 55 the car is at rest.

It is evident that by lifting either side handle, T, the lever R will take its fulcrum at the opposite end in the keeper S, as in dotted lines in Fig. 2, and the rod P will be lifted to raise 60 the frame N, and lift the bar H to uncouple

the cars, and the rod O or lever R of either car may be operated to release either end or head of the coupling-bar.

By the use of my improvement the cars couple automatically as they come together, 70 and may be uncoupled either from their tops or from either side, and without requiring the trainmen to go between them and expose themselves to injury.

It is obvious that when cars are coupled by 75 my improved couplings the draw-heads A, draw-bars E, and coupling-bars H form a continuous yielding connection throughout the whole train, to prevent damage to the cars or couplings by shocks in starting ahead, stopping, or backing, thus insuring the durability 80 of the cars and couplings.

Holes at V in the forward ends of the draw-heads A permit the passage of a pin through an ordinary link to couple on another car by 85 the common link-and-pin devices, in which case the coupling-bar H will be held in a box or by suitable brackets or catches to the end of the car.

It is desirable at times to prevent the coupling of cars as they come together, as when shunting the cars about the yard or onto sidings, and to accomplish this I provide a projection, W, having a square lower shoulder, which may be drawn through the staple Q 95 when the rod P is lifted and set on top of the staple, as in dotted lines in Fig. 2, to hold the uncoupling-frame bar *n'* up about at the top of the stud or horn L, and for like purpose pins X may be held by chains or cords to 100 the keepers S or to the car-body, so as to be at hand ready to pass into holes Y of the car-body and below lifted lever R. The rounded shape of the lifted cross-bar *n'* prevents catching of the shoulder *h* of the coupling-bar on 105 the horn L as the coupling-bar enters or leaves the draw-head, as will readily be understood.

Having thus described my invention, what I claim as new, and desire to secure by Letters Patent, is—

1. In car-couplings, the draw-head A, made with a front opening, K, having a throat, l, a stud, L, and a rear chamber, F, in combination with the coupling-bar H, having tapering heads H' and shoulders *h*, and a spring, M, 115 for locking the heads H' to the stud L, substantially as herein set forth.

2. In car-couplings, the combination, with the draw-head A, having a stud, L, the headed draw-bar H, pressed on the stud by a spring, 120 and the uncoupling-frame N, of the rod P, extended to the top of the car, and the lever R, pivoted on the rod P and extending to and supported at the side parts of the end of the car, substantially as herein set forth.

ROSCOE ALLEN MERROW.
